UNITED STATES PATENT OFFICE

153,542

DESIGN FOR A PORTABLE AIR
COOLING DEVICERobert A. Owens and Martin J. Owens,
Fort Worth, Tex.

Application September 9, 1946, Serial No. 133,182

Term of patent 3½ years

(Cl. D26—7)

To all whom it may concern:

Be it known that we, Robert A. Owens and Martin J. Owens, citizens of the United States of America, residing at Fort Worth, in the county of Tarrant and State of Texas, have invented a new, original, and ornamental Design for a Portable Air Cooling Device, of which the following is a specification, reference being had to the accompanying drawing, forming part thereof.

Figure 1 is a side elevational view of a portable air cooling device showing our new design.

Figure 2 is a front elevational view thereof, and

Figure 3 is a rear elevational view of our new design.

We claim:

The ornamental design for a portable air cooling device, substantially as shown.

ROBERT A. OWENS.
MARTIN J. OWENS.
